BY
G. M. Nease
ATTORNEY

UNITED STATES PATENT OFFICE.

HAROLD F. PARISH, OF NEW YORK, N. Y., ASSIGNOR TO GRINDEN ART METAL COMPANY, A CORPORATION OF NEW YORK.

METALLIC STRUCTURE SUCH AS DOORS AND THE LIKE.

1,003,784.

Specification of Letters Patent. Patented Sept. 19, 1911.

Application filed August 5, 1910. Serial No. 575,757.

To all whom it may concern:

Be it known that I, HAROLD F. PARISH, a citizen of the United States, and a resident of the borough of Brooklyn, county of 5 Kings, city and State of New York, have invented certain new and useful Improvements in Metallic Structures Such as Doors and the Like, of which the following is a full, clear, and exact description, reference 10 being had to the accompanying drawings, forming part of this specification.

My invention relates to metallic building structures such as doors, windows, frames, paneling, wainscoting and the like, and the 15 object thereof is the provision of means for permanently securing the members of the structure together so that it shall possess great rigidity and strength.

In order to describe the invention briefly, 20 I have shown the same as embodied in a door, but it is to be understood that the same is applicable to other structural work of the character above referred to.

Figure 1 of the accompanying drawings 25 shows in elevation a sheet metal door; Fig. 2 is a sectional view of the upper left hand corner thereof, and Fig. 3 is a perspective view of a section thereof on the line 3—3 (Fig. 2).

Similar reference characters are employed 30 to designate corresponding parts in all the views.

In the structure shown, the frame members, to wit, the stiles 1 and 2, and the top, 35 bottom and lock rails 3, 4 and 5, are connected by means of interlocking slots and flanges, the slots being formed on one set of members and the flanges on the other set. The slots are, in the particular embodiment 40 of my invention illustrated, formed on the stiles, and the flanges are formed on the rails. The panel members 6 and 7 are also provided with flanges which project into the 45 slots on the stile members, and also project into similar slots formed on the interior margin of the rail members. These interlocking flanges and slots are shown most clearly in Fig. 3, in which the stile 2 is shown as formed with two marginal slots, 50 one of which 8, receives the flanges 10 formed on the end members, and the other formed on stay 11 which receives flanges 11 formed on stay

members 12. This arrangement of the slots and flanges forms no part of my invention. These flanges and slots interlock tightly and hold the structure together with sufficient 55 rigidity to enable it to be assembled and handled without further locking means; but some further fastening means by which the members of the structure shall be permanently locked together are required to fit the structure for actual service, and in order to accomplish this I cut away or form apertures or openings 15 in the walls of the slots so that the flanges of the interlocked members 60 are exposed at various points, as shown in Figs. 2 and 3. The exposed surfaces of the different members are then united by filling the openings with molten metal which 65 fuses the exposed portions of the different members virtually into an integral structure. This is accomplished by a suitable welding apparatus, preferably one operating on the electric arc principle. The metal which is thus fused into the openings 15 70 completely fills them, and projects sufficiently above the surface of the structure so that the inequalities can be all ground away, leaving a perfectly smooth and even 75 surface which when furnished cannot be distinguished from the remainder of the structure owing to the perfect union between the fused metal connections and the frame members of the structure.

I claim:

1. A metallic structure of the character described, having frame members provided with interlocking slots and flanges, the slotted member being cut away to form 85 openings at points to expose the flanges on the interlocked member, and fused connections in said openings which are united to the flanged and slotted members and fill the openings.

2. In a metal door, a sheet metal part 95 having an interiorly grooved flange, said flange being notched at the edge thereof, the notch and groove being in communication, a member in engagement with said part having a flange disposed in said groove, said 100 flanges having a welded connection therebetween at said notch.

3. In a metal door, sheet metal stiles and stiffening members, said stiles having inter-

riorly grooved flanges at the inner edges thereof, said stiffening members having flanges adapted to enter the grooves in the stile flanges, said stile flanges having notches 5 in the edges thereof, the respective notches and grooves being in communication, said stiffening member flanges projecting out

into said notches and having welded connections with the stile flanges at said notches.

HAROLD F. PARISH.
